STEM STRUCTURE FOR ELECTRON TUBES

Gordon T. Howes, Belmont, Calif., assignor to
Eitel-McCullough, Inc., San Bruno, Calif., a
corporation of California

Application June 2, 1947, Serial No. 751,847

1 Claim. (Cl. 250—27.5)

1

The invention relates to electron tubes such as vacuum tubes, and more particularly to an improved stem structure for such tubes.

The principal object of the invention is to provide a compact stem structure which affords terminal connectors for an electrode and also provides an exhaust tubulation for the tube envelope.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the claim.

Referring to the drawing the single figure is a vertical sectional view of an electron tube embodying the improvements.

In terms of broad inclusion, the improved electron tube comprises an envelope enclosing an electrode, and a tubular metallic stem member on the envelope, which member is ported into the envelope to provide an exhaust tubulation and projects externally of the envelope to provide a terminal for the electrode, the outer end of the member having its side walls compressed together to close the tubulation. In the preferred construction a pair of coaxial stem members are provided, the inner of which serves as the exhaust tubulation.

In greater detail, and referring to the drawing, the improved stem structure is shown in a diode type of electron tube, it being understood that the improvements may be incorporated in tubes having more electrodes such as triodes or the like. The tube illustrated is a diode of small physical size adapted for use in compact spaces such as in a probe, and comprises an elongated evacuated envelope having a cylindrical wall section 2 of vitreous material such as glass. An anode 3 at one end of the envelope is formed by the inner end of a metallic rod 4 such as tungsten sealed to the upper end of the wall section 2.

A cathode is supported by the improved stem structure at the other end of the envelope. This stem structure comprises an outer tubular metallic stem member 7 sealed to the lower end of wall section 2, and an inner metallic stem member 8 coaxial with the outer member. These stem members provide terminal connectors for the cathode, and by their coaxial arrangement are adapted for plugging into a socket or the like. The inner stem member 8 is also tubular and is ported into the envelope to provide an exhaust tubulation. After evacuation the tubular member 8 is pinched off at tip 8 to compress the side

2

walls of the tubulation together to seal the envelope. To facilitate this pinching off operation the inner stem member 8 is preferably made of a relatively soft metal such as copper.

5 An extension 11 of thinner wall metal tubing is brazed to member 8 and is aligned with another section of tubing 12. These sections are connected together and electrically isolated by a sealing ring 13 of vitreous material such as glass. A metal supporting sleeve 14 is brazed at the upper end to stem section 12 and at the lower end to outer member 7 at braze 16. By this arrangement the inner parts of the stem structure may be assembled as a unit and inserted into the open end 15 of the outer stem member 7, the parts being finally secured together by the braze 16 at the lower registering edges.

The cathode illustrated is of the indirectly heated type comprising an emitter body 17 heated 20 by a resistance coil 18. Body 17 may be of nickel coated with suitable oxides for electron emission purposes, in accordance with the common practice of making cathodes of this kind. The cathode body 17 is connected to the outer stem member 7 by supporting wires 19 projecting from tubular piece 12. Heater coil 18 is surrounded by a heat shield 20 and is connected at the upper end to cathode body 17 and at the lower end to a center rod 21 secured to inner stem member 8. A ring 22 formed at the lower end of rod 21 facilitates brazing this rod in position. By these connections it will be seen that the cathode body is connected to the outer stem member and that the heater is connected across the inner and outer stem members. It is understood that the cathode 25 may be of the filamentary type such as a thoriated tungsten filament, in which case the filament would be connected across the terminal members in a manner similar to the heater coil 18.

40 In order to shield the envelope and other parts of the tube from material sputtered from the cathode a tubular metal shield 23 is preferably mounted on sleeve 14 to project upwardly into the regions surrounding the cathode. For similar reasons a transverse shielding disk 24 is preferably provided below the cathode body, held in shield 23 by a retaining ring 26. It is understood that the entire cathode structure is mounted on the inner stem assembly prior to inserting sleeve 14 45 into the outer stem member 7. After inserting the inner stem assembly the final braze 16 is made to complete the envelope. At this stage the tubulation member 8 is, of course, open ended for purposes of exhausting the envelope. Following evacuation the exhaust tubulation is pinched off

at tip 9 to seal the envelope and leave the tubulation in condition to function as a terminal member.

The improved stem structure above described, incorporating the exhaust tubulation as a terminal connection for the cathode, has special advantages in tubes of small physical size where space is at a premium.

I claim:

An electron tube comprising electrodes and an envelope, and a tubular metallic stem member supported on the envelope and connected to one of the electrodes, said member having an unobstructed passage communicating with the interior of the envelope to provide an exhaust tubulation and projecting externally of the envelope, the

outer end of said member having its side walls compressed together to close the tubulation, said outer projecting end being exposed externally of the envelope to provide a rigid terminal prong.

GORDON T. HOWES.
